UNITED STATES PATENT OFFICE.

WILLIAM McCONNELL, OF NEW YORK, N. Y.

DESIGN FOR AN ELECTRIC-LIGHT FIXTURE.

SPECIFICATION forming part of Design No. 33,916, dated January 15, 1901.

Application filed December 21, 1900. Serial No. 40,692. Term of patent 7 years.

To all whom it may concern:

Be it known that I, WILLIAM McCONNELL, a citizen of the United States, and a resident of the city of New York, borough of Brooklyn, in the county of Kings and State of New York, have invented and produced a new and original Design for an Electric-Light Fixture, of which the following is a specification, reference being had to the accompanying drawing, forming a part thereof, in which is represented a perspective view of an electric-light fixture embodying the features of my design.

The leading features of the design consist in the representation of a floral stalk and a jardinière or flower-pot, from which the stalk extends, together with a flower, in the center of which an electric-light bulb appears.

The minor features of the design consist in

the stem of the flower and leaves on the stem, together with a full-blown blossom at one portion of the stem, the stamen of which blossom is in the form of an electric-light bulb, together with the decorative character of the jardinière or flower-pot. 25

Having thus described my invention, I claim as new and desire to secure by Letters Patent—

The design for an electric-light fixture herein shown and described. 30

In testimony whereof I have signed my name to this specification in the presence of two subscribing witnesses.

WILLIAM McCONNELL.
